UNITED STATES PATENT OFFICE

GEORGE W. MACKENZIE, OF BEAVER, PENNSYLVANIA

DESIGN FOR A ROBOT SAFETY SIGNALING DEVICE

Application filed January 2, 1932. Serial No. 42,351. Term of patent 7 years.

To all whom it may concern:

Be it known that I, GEORGE W. MACKENZIE, a citizen of the United States, residing at Beaver, in the county of Beaver and State of Pennsylvania, have invented a new, original, and ornamental Design for a Robot Safety Signaling Device, of which the following is a specification, reference being had to the accompanying drawings, forming part hereof.

Figure 1 is a front elevational view of the robot showing my new design; and,

Figure 2 is a side elevational view thereof.

I claim:

The ornamental design for a robot safety signaling device, as shown.

GEORGE W. MACKENZIE.
